[57] CLAIM

The ornamental design for a golf club head, as shown and described.

DESCRIPTION

FIG. 1 is a front elevation view of a golf club head according to the invention;

FIG. 2 is a side elevation view on line 2—2 of FIG. 1;
FIG. 3 is a side elevation view on line 3—3 of FIG. 1;
FIG. 4 is a top view of a golf club head according to the invention;

FIG. 5 is a bottom view of a golf club head according to the invention;

FIG. 6 is a rear perspective view of a golf club head according to the invention;

FIG. 7 is a front elevation view of a second embodiment of a golf club head according to the invention;

FIG. 8 is a side elevation view on line 8—8 of FIG. 7;
FIG. 9 is a side elevation view on line 9—9 of FIG. 7;

FIG. 10 is a top view of the second embodiment of a golf club head;

FIG. 11 is a bottom view of the second embodiment of a golf club head; and,

FIG. 12 is a rear perspective view of the second embodiment of the golf club head shown in FIGS. 7-11.

The undisclosed front view of the second embodiment is identical to that disclosed in the first embodiment.
